[57] CLAIM

The ornamental design for tray with cover, as shown and described.

DESCRIPTION

FIG. 1 is a perspective view of a tray with cover showing my new design;

FIG. 2 is a front elevation thereof;

FIG. 3 is a front elevation of the tray without the cover thereof, the rear side elevation being a mirror image;

FIG. 4 is a right side elevation of the tray without the cover thereof;

FIG. 5 is a bottom plan view of the tray thereof;

FIG. 6 is a left side elevation of the tray without the cover thereof;

FIG. 7 is a top plan view of the cover thereof;

FIG. 8 is a front elevation of the cover without the tray thereof, the rear side elevation being a mirror image;

FIG. 9 is a right side elevation of the cover without the tray thereof, the left side elevation being a mirror image; and

FIG. 10 is a sectional elevation taken on line 10—10 of FIG. 5 & 7 thereof.
